UNITED STATES PATENT OFFICE.

CHARLES E. SARGENT AND ROY B. PEEBLES, OF CHICAGO, ILLINOIS, ASSIGNEES TO CHICAGO CARD CUTTING COMPANY, OF CHICAGO, ILLINOIS, A CORPORATION OF ILLINOIS.

CARD COUNTING AND STACKING MACHINE.

No. 927,080.

Specification of Letters Patent.

Patented July 6, 1909.

Application filed October 10, 1907. Serial No. 396,761.

To all whom it may concern:

Be it known that we, CHARLES E. SARGENT, and ROY B. PEEBLES, citizens of the United States, residents of Chicago, in the county of Cook and State of Illinois, have invented certain new and useful Improvements in Card Counting and Stacking Machines, of which the following is a full, clear, and exact description.

10 This invention relates to certain new and useful improvements in card counting and stacking machines, and designs to furnish a simple, practical and efficient device for counting cards, business cards, or any other 15 thin, light sheets or plates—such as sheet metal blanks, card board, paste board and the like.

One of the objects of this invention is to furnish friction feed devices operating positively to advance and propel the cards.

Another object is to provide means for stacking up the counted cards and subsequently moving the stacks away from the stacking apparatus and into a convenient 25 position for the operator to remove them.

Another object is to provide means for stacking up an equal number of cards in each stack.

Another object is to simplify and otherwise improve devices of this class whereby it may contain important advantages not before known.

To such end the invention consists in certain novel features of construction and arrangement; and in certain new combinations of parts, a description of which will be found in the following specification, and the essential features of which will be more definitely pointed out in the claims appended 40 hereto.

The invention is clearly illustrated in the drawings furnished herewith, in which—

Figure 1 is a side elevation of a machine embodying our improvements. Fig. 2 is a plan view thereof. Fig. 3 is a view partly in side elevation and partly in vertical longitudinal section, of certain card counting and stacking mechanism. Fig. 4 is a plan view of certain parts seen in Fig. 3. Fig. 5 is a plan view of certain pulleys, a shaft and frame. Fig. 6 is a detail rear elevation of certain trip mechanism. Fig. 7 is a longitudinal section, taken on line 7—7—Fig. 2. Fig. 8 is a horizontal section taken on line

8—8—Fig. 7. Fig. 9 is a perspective view 55 of a foot. Fig. 10 is a vertical cross section taken on line 10—10—Fig. 7. Fig. 11 is a similar section taken on line 11—11—Fig. 7. Fig. 12 is a plan view of a table and certain friction rollers.

60 Referring to these drawings, 1 represents a platform which is supported by legs 2.

2^a are two bars, that extend parallel with the platform and are secured to the legs in any suitable manner. Pulleys 3, 4, are 65 journaled in said bars at points immediately beyond the ends of the platform, and said pulleys are connected by a conveyer belt 5, the upper bight of which runs upon the platform 1. The roller 3, is intermittently rotated (by mechanism hereafter described) 70 one revolution at the time so as to intermittently advance the conveyer belt 5, to shift the stacked cards out of the way of the following one.

75 The upper ends of the legs 2, extend across the platform in the form of a yoke 2^b, upon which yoke is supported the operating table 6, in which the cards are counted by mechanism, hereafter described. The table is in 80 the form of a trough or channel having a bottom 7 and sides 8. Two bars 9, 9, (see Figs. 7,—10) are secured along the side edges of table 6, which bars serve as bearings for a number of friction rollers 10, 11, 12, 13, that 85 are rotated to advance the cards along the table. For convenience the rollers 10, 11, will be termed feed rollers, and the rollers 12, 13 advancing rollers. The shafts or spindles 14, of said friction rollers carry pulleys, 15, 16, 17, 18, (see Figs. 1 and 12) which 90 pulleys are belted to drive pulleys 19, 20 by belts 21, 22, the belt 21, passing around the pulleys 17, 18, 19, and the belt 22 around pulleys 15, 16, 20, all of said pulleys being 95 driven in the same direction, that is, in a direction to advance the cards from right to left as viewed in Fig. 1. The rollers are driven at a high rate of speed and the arrangement is such that the roller 12 is 100 driven at a higher rate of speed than the rollers 11, 10, while the roller 13 is driven at a still higher rate of speed. In the arrangement shown, the roller 10, is driven at a higher rate of speed than the roller 11, 105 although this is not material to my invention broadly considered. The roller 10, forces the card through the space between the pul-

ley 11, and a retaining gate, which space is sufficient to allow the card to pass freely therethrough. When the card has passed by the roller 10, the roller 11, carries it on until 5 the roller 12, has taken hold of it. The roller 11, is employed for feeding cards to the roller 12, which are not of sufficient length to reach from the roller 10, to the roller 12. The pulleys 19, 20 are mounted upon a shaft 23, 10 which is journaled in the bars 2^a, and said shaft carries tight and loose pulleys 24, 25 adapted to be belted to a suitable drive pulley. Frequently these machines are placed adjacent to card punching machinery and in 15 such cases it is customary to belt the pulleys 24, 25, directly to the fly wheel of the card punching machinery.

Over the rollers 10, 11, is placed a feed chute or hopper 26, which is preferably 20 made up of a back piece 27 and two sides 28, the sides being screwed or otherwise secured to the flanges 8, of the table 6. Two guide bars 29 are secured to the sides 28 of the chute as at 30, and extend down upon the 25 table 6, their lower ends being adjustably spaced apart by adjusting screws 31. An adjustable back stop 32, is secured to the table 6, by a screw 32^a and nut 32^b, and has an inclined flange 33 upon its forward edge 30 which serves to deflect or crowd the cards forward as they rest upon the inclined face thereof. The stop is slotted longitudinally for the set screw 32^a, so that it may be adjusted backward and forward to accommodate 35 date cards of different lengths. A pair of guide bars 34, are provided upon the table 6, which guide bars are clamped in place by a cross bar 35 which rests upon the rear ends of the guide bars 34, and is clamped there- 40 upon by the set screws 32^a. The bars 34 are adjustably mounted upon a rod 36, and when narrow cards are to be counted the bars 34 may be moved closer to each other and clamped in place by the bar 35 and set 45 screw 32^a.

Directly above the roller 11 is an adjustable gate 37 (see Fig. 7), which is arranged to hold back the cards and to permit one card at the time to pass between said gate and the 50 roller 11. The gate is carried by a stem 38, which is clamped in a post 39, by a set screw 40, and said stem is moved up and down by an adjusting screw 41, that is carried by a bracket 42, and screws into a threaded opening 55 in the end of the stem 38. As shown the bracket 42 and post 39 are supported by the chute 26. By means of this arrangement, a very minute adjustment may be had so as to admit of the passage of only one card at the 60 time through the gate way. This adjustment is also afforded for cards of other thicknesses. The feed roller 10 is arranged to feed the bottom card through the gate way and the roller 11, advances the card to the 65 roller 12, which passes it through the count-

ing mechanism, after which the roller 13, throws it into a receiving receptacle where the cards are stacked up. The weight of the cards is sufficient to produce the necessary friction upon the feed roller 10, but where 70 the cards pass through the counting devices one at the time I have provided friction rollers 43, 44, which bear upon the cards as they pass through and coöperate with the rollers 12, 13, to advance the cards. The rollers 75 43, 44, are journaled in oscillating arms 45 which are pivoted upon the sides 8 of the table 6, and springs 46 are provided to press the rollers 43, 44 down upon the cards.

The counting mechanism is supported upon 80 a plate 47, secured to the table 6, and as shown consists in mechanism arranged to be actuated by the cards as they pass from the rollers 12, 43 to the rollers 13, 44. As shown, this mechanism comprises a toothed wheel 48 85 journaled upon a stud 49, and devices for rotating the wheel 48 in a step by step movement. An arm 50 is pivoted upon the stud 49, and bears a spring pressed pawl 51 that engages the teeth of the wheel 48, and said 90 arm has adjustably secured to it a leg 52, which carries upon its lower end a foot 53, beneath which the cards pass, said foot being lifted by the cards as they pass under it. In this way the wheel 48 is advanced one step 95 each time that a card passes by the foot. An adjustable stop 54, is provided to limit the upward movement of the arm 50, said stop being shown in the form of a screw, threaded in a lug 55. A spring 56, confined 100 between said lug 55 and the arm 50, serves to return the arm and foot to normal position. A spring detent 57, is also provided to prevent movement of the wheel 48 while the arm 50 is being returned to normal position. 105 The wheel 48 should be provided with as many teeth as the required number of cards in each stack.

After the cards pass through the counting mechanism they are thrown into the receiving receptacle of a stacker, when they fall one upon the other in a pile or stack. As shown this stacker consists of a stop or hood 58 which is secured to the platform 6 and extends upward as at 59, and then inclines forward so that it will catch the cards and stack them upon each other as they are thrown from the rollers 13, 44. A pair of side walls 61, are secured to the platform on either side of the stop or hood 58, and coöperate with the stop 58 to stack up the cards. The side walls are adjustably clamped upon the platform, as by screws 62, that pass through slots in the base or flange 63 of the walls 61, whereby the walls may be adjusted 115 toward or away from each other for cards of different widths. As soon as the predetermined number of cards have been stacked upon each other in the stacker, certain mechanism operates to arrest the cards in the chute 120 125 130

and to throw into gear the mechanism for advancing the conveyer belt 5, and this mechanism will now be described.

The spindle 64 of the pulley 3, extends out beyond the side bar 2^a, and bears a pulley 65, loosely mounted upon said spindle, but frictionally connected thereto by a device comprising sleeves 66, 67 fast upon the spindle, and a spring 68 interposed between the sleeve 67 and the pulley 65. The spring acts to hold the pulley in frictional contact with the sleeve 66, and whenever the pulley 3 is permitted to turn, the rotation of the pulley 65 will consequently rotate the pulley 3. The pulley 65 is connected with a pulley 69 upon the shaft 23, by a belt 70, but inasmuch as the pulley 3, and shaft 64 are held stationary during a portion of a cycle of operation, pulley 65 must necessarily turn upon the shafts 64 during said stationary period inasmuch as the shaft 23 is a constantly rotating shaft.

In order that the pulley 3 may be held stationary during the period that cards are being stacked upon the conveyer belt, mechanism is provided for arresting the movement of said pulley during said period, which mechanism is controlled by the counting mechanism in such a manner that whenever the predetermined number of cards have passed under and actuated the foot 53, the wheel 48 will then trip the stop mechanism and allow the pulley 3 to be given one revolution. As shown a lug 71 is secured upon the pulley 3, which lug is arranged to engage a stop 72, which is carried by a stop lever 73, pivoted to the plate 47, at 74, and arranged to be engaged by a latch or trigger 75, to hold it in position for engagement with the lug 71. A bell crank lever 76 is pivoted to the bar 2^a, as at 77, and engages the stop lever 73 by means of a slotted arm 78, that engages a pin 79 on the lever, and a spring 80 is attached to the other end of the lever 76 and acts to swing the slotted end of the arm 78 upward, thereby raising the stop 72 out of the path of the lug 71. Fig. 3 shows the parts in such position in full lines, and with the parts in locked position in dotted lines. The surface of the pulley 3 is partially cut away at a point adjacent to the lug 71, so as to permit of the movement of the lever 76, toward the center of the pulley.

The trigger 75 is in the form of an angle lever and is pivoted to the plate 47, and has an abutment or shoulder 81, that is arranged to engage the underside of the stop lever 73, to lock the stop 72 in its operative position, that is in the position for engagement with the lug 71. This position of the trigger is shown in full lines in Fig. 6. A spring 82 is provided for yieldingly holding said trigger in engagement with the stop lever, and a pin 83 that extends back from the wheel 48, is arranged to strike an arm 84^a of the trigger

75 to swing the shoulder 81 out of engagement with the stop lever. From this it will be understood that whenever the wheel 48 makes one complete revolution the pin 83 strikes the trigger 75 and disengages it from the stop lever, whereupon the spring 80 swings the lever 76 upon its pivot and raises the stop 72 out of engagement with the lug 71, allowing the pulley 3 to be turned by the belt and pulley connection with the drive shaft 23. The pulley being free to turn, is revolved in the direction of the arrow in Fig. 3, and in the course of one revolution the lug strikes the lever 76, swings it against the pull of the spring, swings the arm 78 down and restores the stop 72 to operative position in the path of the lug 71, the shoulder 81 on the trigger 75 swinging under the end of the stop lever 73 and locking it against the action of the spring 80 so that after the lug 71 again reaches the stop 72 it will be arrested thereby, and the belt 5 held stationary while another stack of cards accumulates in the stacker.

Whenever the trigger is actuated by the pin 83 on the ratchet wheel, and the conveyer belt consequently advanced, it becomes necessary to arrest or hold back the cards in the chute, and this is accomplished by a foot 84 that is carried by the stop lever 73 and arranged to be depressed thereby to stop the card, should one have been fed underneath it, or if not, to obstruct its passage until the foot 84 is again raised. Said foot comprises an adjustable stem 85, preferably made in two parts, connected together by a screw connection, one of the parts being slotted so that one may be moved longitudinally of the other for its adjustment. The foot 84 is connected to one end of the stop lever by a screw 86, and bears upon its lower end two rollers 87 which impinge upon the oncoming card whenever the pulley 3 is set in motion.

The operation of the machine is as follows: The operator fills the chute 26 with cards A, and the roller 10 feeds the bottom one through the gateway between the roller 11 and the gate 37. This gate should be adjusted so as to leave a space between it and the roller 11 of about the thickness of one card, whereby only one card at the time can pass through the gate way. The cards immediately above the lowest card, will strike the gate as they are moved forward by the action of the roller, but as soon as the bottom card has passed through the opening, the one immediately above will take its place and pass through. The roller 11 passes the card under the foot 84 and on to the rollers 43, 12, and they in turn pass it under the foot 53, when it advances the ratchet wheel one tooth. The rollers 12, and 13, are positioned closely enough that the rollers 43, 12 will pass the card to the rollers 44, 13, after

which the rollers 44, 13 throw the card into the stacker. The rollers 12, 13 are timed to revolve at a higher rate of speed than the rollers 10, 11, so that the card will be passed 5 completely by the foot 53, before the following card reaches the foot. This allows the foot to resume its original position after being raised by the card, before the following one reaches it. As each card passes under 10 the foot 53, the ratchet wheel is advanced one step, until the pin 83 strikes the trigger 75, and releases the stop lever 73, whereupon the foot 84 is depressed closing up the passage to the roller 12, the pulley 3 is released 15 from the stop 72, and is rotated by the belt 70, thus advancing the conveyer belt 5, one step and carrying the stack, which has just accumulated, out of the stacker. As the pulley 3 approaches one complete revolution, 20 the lug 71 strikes the lever 76, restores the stop 72 to operative position, whereupon the trigger 75 is again swung into engagement with the stop lever 73, by the spring 82.

An emergency lever 90 is pivoted to the 25 plate 47, and is arranged to be swung into engagement with the trigger 75 so as to release the stop lever and close the passage-way to the counting mechanism. The platform is of some length so that the operator 30 may have plenty of time to remove the packs or stacks of cards from the conveyer belt before they reach the end of the platform.

By means of this construction we have been enabled to count and separate into 35 stacks, from 300 to 600 cards per minute, without any danger of error. The gate 37 can be adjusted to accommodate cards of different thickness, the back stop 32 can be adjusted to cards of different lengths, and 40 the guide bars 29, 34 to cards of different widths. The ratchet wheel 48 can be replaced with one of more or less number of teeth so as to separate the cards into packages or stacks of more or less cards, as desired. In other words the apparatus is universally adjustable for all sizes of cards within a given limit and for various thickness.

We are aware that various alterations and modifications of this device are possible without departing from the spirit of our invention and we do not therefore desire to limit ourselves to the exact form shown and described.

We claim as new and desire to secure by 55 Letters Patent:

1. In a device of the class described, the combination of a feed roller for feeding individual cards from a stack of cards, counting mechanism including a toothed wheel, and a 60 foot actuated by the passage of cards thereunder and carrying a pawl for rotating the tooth wheel, advancing rollers which run at a higher rate of speed than the feed rollers, and a stacking mechanism comprising an 65 intermittently advanced belt upon which the

counted cards are received, a stop against which the cards are thrown by the advancing rollers and connections between the belt and counting mechanism for controlling the advancement of the belt. 70

2. In a device of the class described, the combination of feed rollers for feeding individual cards from a stack of cards, a retarding gate arranged above one of said feed rollers, counting mechanism including a toothed 75 wheel, and a foot actuated by the passage of cards thereunder and carrying a pawl for rotating the tooth wheel, advancing rollers which run at a higher rate of speed than the feed rollers, and a stacking mechanism comprising an intermittently advanced belt upon 80 which the counted cards are received, a stop against which the cards are thrown by the advancing rollers and connections between the belt and counting mechanism for controlling the advancement of the belt. 85

3. In a device of the class described, the combination of feeding mechanism, advancing mechanism, counting mechanism, a card arresting foot interposed between the feeding 90 and advancing mechanism operated by the counting mechanism and arranged to impinge upon a fed card, whenever a predetermined number of cards have passed through the counting mechanism, and stack- 95 ing mechanism.

4. In a device of the class described the combination of a feeding mechanism, counting mechanism, card arresting mechanism having a foot interposed between the feeding mechanism and counting mechanism, and adapted to impinge upon a fed card, whenever a predetermined number of cards have passed through the counting mechanism. 100

5. In a device of the class described the combination of a feeding mechanism, card arresting mechanism having a foot for impinging upon the cards, counting mechanism actuated by the passage of the cards there- 110 through and operating to actuate the arresting mechanism, stacking and conveying mechanism.

6. In a device of the class described, the combination of a counting mechanism, an 115 endless conveyer belt for removing the counted cards, a drive pulley therefor, a continually moving driving belt, a pulley over which said driving belt passes, a frictional connection between said pulleys, and 120 stop mechanism operated by the counting mechanism, for arresting the movement of the conveyer belt.

7. In a device of the class described, the combination of a card counting mechanism, 125 an endless conveyer belt for removing the counted cards, a drive pulley therefor, a continually moving driving belt, a pulley over which said driving belt passes, a frictional connection between said pulleys, stop mech- 130

- anism for arresting the movement of the conveyer, releasing mechanism for the stop operated by the counting mechanism, and stop restoring mechanism.
5. 8. In a device of the class described the combination of card feeding mechanism, card advancing mechanism, a counting mechanism, card arresting mechanism, an intermittently movable conveyer for removing the counted cards, and mechanism for operating the arresting mechanism, and simultaneously setting in motion the conveyer.
9. In a device of the class described, the combination of card feeding and advancing mechanism, a card counting mechanism, card arresting mechanism, an intermittently movable endless belt conveyer for removing the counted cards, stop mechanism for arresting the belt, actuated by the counting mechanism and devices for operating the card arresting mechanism, and simultaneously setting in motion the conveyer.
10. In a device of the class described the combination of card feeding mechanism, card advancing mechanism, a counting mechanism, card arresting mechanism, a conveyer, mechanism adapted to operate said conveyer, stop mechanism, operated by said counting mechanism simultaneously with the card arresting mechanism to control the movement of the conveyer.
11. In a device of the class described the combination of card feeding mechanism, card advancing mechanism, a counting mechanism, card arresting mechanism, a suitably operated conveyer, and stop mechanism containing a stop arranged to arrest the movement of the conveyer, mechanism operated by the counting mechanism for actuating the stop to release the conveyer, and means for restoring the stop to operative position.
12. In a device of the class described the combination of a stack shifter, and mechanism for intermittently actuating said stack shifter comprising a suitably driven pulley, a stop arranged to arrest the movement of the pulley, mechanism operated by the passage of a predetermined number of cards therethrough for throwing said stop out of operative position, and mechanism for restoring the stop to operative position.
13. In a device of the class described, the combination of a stack shifter, continually moving mechanism for actuating said shifter, shifter arresting mechanism, trip mechanism operated by the passage of a predetermined number of cards therethrough for throwing said shifter arresting mechanism out of operation and restoring mechanism for restoring the arresting mechanism into operative position.
14. In a device of the class described the combination of a stack shifter, and controlling mechanism for said stack shifter comprising means for advancing the shifter, stop mechanism for arresting the shifter, suitably operated trip mechanism for throwing said stop mechanism out of operative position, and mechanism operated by the shifter for restoring said stop mechanism to operative position.
15. In a device of the class described the combination of a stack conveyer, a suitably operated pulley for advancing the conveyer, conveyer arresting mechanism, suitably operated trip mechanism for throwing said conveyer arresting mechanism out of operation, and restoring mechanism.
16. In a device of the class described the combination of a stack conveyer, controlling mechanism for said stack conveyer comprising stop mechanism, devices for throwing said stop mechanism out of operative position, and mechanism operated by the conveyer for restoring said stop mechanism to operative position.
17. In a device of the class described the combination of card counting mechanism, a stack shifter and controlling mechanism for said stack shifter, comprising stop mechanism, devices operated by the counting mechanism for throwing the stop mechanism out of engagement with the stack shifter, and mechanism operated by the shifter for restoring said stop mechanism into operative position.
18. In a device of the class described the combination of card counting mechanism, a stack conveyer and controlling mechanism for said stack conveyer, comprising stop mechanism, devices operated by the counting mechanism for throwing the stop mechanism out of engagement with the stack conveyer, and mechanism operated by the conveyer for restoring said stop mechanism into operative position.
19. In a device of the class described the combination of card feeding mechanism, card counting mechanism, card arresting mechanism, a stack shifter, and mechanism for simultaneously operating the card arresting mechanism, and stack shifter, comprising a stop lever, a foot and a stop carried thereby, said stop being arranged to normally hold the shifter in an inactive position, and mechanism operated by the shifter for operating the stop lever to raise the foot and restore the stop to operative position.
20. In a device of the class described the combination of card feeding mechanism, card counting mechanism, card arresting mechanism, a stack shifter, a stop for arresting movement of the shifter, a trip mechanism for simultaneously holding said card arresting mechanism out of operative position, and said shifter stop mechanism in operative position, said trip mechanism being operated by said card counting mechanism for simultaneously bringing said card arresting mech-

anism into operative position, and stop out of operative position, and mechanism for restoring said stop mechanism to operative position and simultaneously bringing the card arresting mechanism out of operative position.

21. In a device of the class described the combination of card feeding mechanism, card counting mechanism, a card arresting foot, a trip mechanism for said arresting foot actuated by said counting mechanism, and restoring mechanism for said arresting foot.

22. In a device of the class described the combination of a conveyer belt, a pulley, a friction driving mechanism for said pulley, a stop lug, a stop normally engaging said lug, mechanism for intermittently throwing said stop out of engagement with said lug, and a spring operated lever arranged to be actuated by said lug to restore the stop to operative position.

23. In a device of the class described the combination of a conveyer belt, a pulley, a friction driving mechanism for said pulley, a stop lug, a stop normally engaging said lug, a spring operated lever arranged to be actuated by said lug to restore the stop to operative position, and a trigger operating to alternately throw the stop out of engagement with the lug and to hold the stop in operative position.

24. In a device of the class described the combination of advancing mechanism, a foot adapted to be actuated by the passage of the cards, a pawl carried thereby, a toothed wheel, actuated by said pawl, and having a trip pin, a trigger actuated by the trip pin on said toothed wheel, and a card arresting mechanism normally held out of operative position by said trigger.

25. In a device of the class described the combination of advancing mechanism, a foot

adapted to be actuated by the passage of the cards, a pawl carried thereby, a toothed wheel, a trigger actuated by said toothed wheel, a card arresting mechanism normally held out of operative position by said trigger, a stack shifter and controlling mechanism for said shifter, arranged to alternately release said controlling mechanism and hold the same in locked position.

26. The combination of feeding mechanism, a foot adapted to be actuated by the passage of the cards, a pawl carried thereby, a toothed wheel, a pin thereon, a trigger adapted to be tripped by said pin, a card shifter, and a shifter controlling mechanism adapted to be set in motion by said trigger.

27. In a device of the class described, the combination of a card chute, adjustable side bars therein, an operating table, adjustable side bars therein, mechanism for feeding the cards from said chute one at the time, and mechanism for cutting and stacking said cards.

28. In a device of the class described, the combination of a card chute, an operating table, a gate, an adjustable back stop for the cards arranged to deflect the cards toward the gate, mechanism for feeding the cards from said chute one at the time, counting mechanism and mechanism for stacking said cards into individual stacks.

In witness whereof we have executed the above application for Letters Patent of the United States this 4th day of October, 1907, at Chicago, county of Cook and State of Illinois.
